HEAT-EXCHANGER COMPONENTS

The present invention relates to heat-exchanger components or elements which are capable of economically transmitting heat currents up to a magnitude of approximately 1,000 kcal./m.²hr. and which are made of materials, especially plastics, whose heat conductivity and temperature stability are approximately 100 times lower than those of metals which so far have been exclusively employed for producing such heat-exchanger components or elements.

It is an object of the present invention to provide heat-exchanger components or elements of the above-mentioned type which are designed so as to have an inherent static stability sufficient for all practical purposes. More specifically, the heat-exchanger elements according to the invention should have such a high bending strength at least in one cross-sectional direction that, when the opposite ends of such an element which extends horizontally are rigidly clamped or rest on fixed supports, it will be able to bridge distances of several meters without bending especially between these ends. In addition to being capable of supporting their own weight, the heat-exchanger elements according to the invention should also be able to take up the forces caused by the medium which flows through these elements. A further important object of the invention consists in so designing these heat-exchanger elements as to permit them to be manufactured at a very low cost by being produced within a very short time and of a very small quantity of material and also by means of simple conventional machines as, for example, extruders.

For attaining these objects, the invention provides that each of the heat-exchanger components or elements consists of a plurality of pipes which have thin walls and are integrally interconnected by webs so as to form a unit which may be cast, injection-molded or extruded in one piece.

It is an important feature and advantage of the invention that such a heat-exchanger element may be easily made to conform to uneven wall surfaces on which it is to be installed by permitting the central longitudinal axes of the individual thin-walled pipes as well as the central longitudinal planes of their connecting webs to be disposed within a rectilinear, wavy, or zigzag-shaped transverse plane or within a transverse plane whose different parts may extend at different angles or in different directions to one another. These different shapes of the heat-exchanger elements may be very easily produced in the course of their manufacture and also at least to some extent during their installation.

It is one of the numerous advantages of such a heat-exchanger element that it may be connected in a very simple manner to headers, which may consist of pipes, drums, boxes or the like, by cutting out the ends of the connecting webs so that short individual pipe ends project from the remaining main body of the webs which may then be fitted into bores in the headers or be anchored thereto via short nipples secured to the headers.

Another feature of the invention resides in the provision of suitable wedge means for securing these individual pipe ends of the heat-exchanger element within the bores of the header. These wedge means may consist, for example, of coiled compression springs. One end of such a spring bears upon the inner wall of the header opposite the bore into which the respective pipe end is inserted, the other end of each coil spring being formed into or attached to a conical spreader which engages under the pressure of the coil spring in the confronting pipe end to dilate it.

The invention further provides that several similar heat-exchanger elements may be combined so as to form a larger heat-exchanger block, e.g., by means of spacing members whose opposite sides conform to the contours of one side of each of two adjacent heat-exchanger elements.

These and additional features and advantages of the present invention will become further apparent from the following detailed description thereof which may be read with reference to the accompanying drawing in which:

FIG. 1 shows a perspective view of a simple heat-exchanger element which is disposed within a straight transverse plane;

FIG. 2 shows a perspective view of a heat-exchanger element or unit which has a wavy cross section;

FIG. 3 shows a perspective view of a heat-exchanger element of a zigzag-shaped cross section;

FIG. 4 shows a perspective view of a heat-exchanger element in which several pairs of adjacent parallel pipes are laterally offset relative to one another;

FIG. 5 shows a plan view of the connecting end of a heat-exchanger element;

FIGS. 6 to 9 show cross-sectional views of four different arrangements for connecting a heat-exchanger element to a header;

FIGS. 10 and 11 show cross-sectional views of another arrangements for connecting a heat-exchanger element to a header by means of compression springs;

FIGS. 12 to 14 show plan views of compression springs of different shapes;

FIG. 15 shows a perspective view of a part of a heat-exchanger block;

FIG. 16 shows a plan view of a part of a heat-exchanger element whose connecting webs are provided with bores; while

FIGS. 17 and 18 show schematic illustrations of two different heat-exchanger blocks each of which consists of a combination of a plurality of heat-exchanger elements.

FIG. 1 shows a perspective view of a heat-exchanger element 1 drawn to slightly less than its natural size. This unit consists of a plurality of parallel pipes 2 of a circular cross section and any desired length which are integrally connected to one another by webs 3. The pipes 2 and connecting webs 3 of this embodiment of the invention form a generally flat unit in which the axes of the pipes 2 and the longitudinal planes of the webs 3 are disposed within a common straight transverse plane. The maximum width or thickness of this heat-exchanger element 1 is equal to the diameter d of the pipes 2.

FIG. 2 illustrates a heat-exchanger element 4 of a modified shape in which the axes of the individual pipes 2 and the longitudinal planes of the webs 3 are disposed within a wavy transverse surface and the maximum width or thickness of the entire heat-exchanger element has a value a .

FIG. 3 shows another heat-exchanger element 5 according to the invention in which the axes of adjacent pipes 2 and the longitudinal planes of the connecting webs 3 are disposed within a zigzag-shaped transverse surface, while FIG. 4 shows

a heat-exchanger element 6 in which the axes of alternate pairs of pipes 2 and the connecting webs 3 of these pairs are disposed within two parallel transverse planes which are laterally offset from each other, the connecting webs between these pairs being disposed at substantially equal oblique angles to these planes but extending alternately in opposite directions. The entire heat-exchanger element as shown in FIGS. 3 and 4 has a maximum width or thickness b or c , respectively.

If the heat-exchanger elements or units 1, 4, 5 and 6 according to FIGS. 1 to 4 consist of a suitable plastic, they may be manufactured very easily and at low cost, especially if they are produced by extrusion, although they may, of course, also be made by casting or injection-molding. If produced by extrusion, these heat-exchanger elements may be given a sufficient stability by being extruded in one piece from the nozzle of an extruder which is made of a corresponding shape. Considering the relatively low solidity of the plastic, it is then advisable to make the wall thickness r of each pipe 2 approximately equal to one tenth of its diameter d . If a heat-exchanger element as shown in FIGS. 1 to 4 is composed, for example, of 10 or more pipes 2 which extend substantially horizontally and, for example, within a substantially vertical plane one above the other, it is capable of spanning a distance of several meters without bending noticeably between its supported ends.

If such a heat-exchanger element 1, 4, 5 or 6 is to be connected at one side 8 to a header 7 as shown in FIGS. 6 to 11, it is advisable to cut out the ends of the connecting webs 3 for a distance e from the end surfaces 9 of the pipes 2, as shown diagrammatically in FIG. 5, so that short individual connecting ends 10 project from the main webbed part of the element.

As illustrated diagrammatically in FIG. 6, the wall 11 of the header 7 is provided with a series of parallel bores 12 into which the projecting pipe ends 10 of a heat-exchanger element 1 according to FIG. 1 are to be inserted. These pipe ends 10 may then be firmly connected and tightly sealed to the wall 11 of the header and to the walls of the bores 12 in this wall 11, e.g., by means of a two-component casting resin 13.

FIG. 7 illustrates a mechanical connection of the pipe ends 10 to the wall 11 of the header 7 by means of tubular screws 15 each of which has a substantially conical head 14. When these tubular screws 15 are screwed into the openings of the pipe ends 10, screw threads cut into the pipe ends 10 and the conical heads 14 of these screws spread the free extremities of the pipe ends 10 which project into the header 7 and extend beyond the bores 12, thereby also clamping the pipe ends 10 securely and tightly to the walls of these bores 12.

FIG. 8 illustrates another type of connection of the pipe ends 10 to header 7, in which nipples 17 are mounted in the bores 12 of the header 7. The nipples 17 have bulb-shaped ends 18 outside the header inserted in the free ends 10 of the pipes; if these free ends are previously heated, they may be easily fitted over these enlarged ends 18 and, on cooling, they will shrink and thus fit tightly and securely on the inserted nipples.

A similar pipe connection is shown in FIG. 9, in which the outer ends 18' of nipples 17', seated in the header 7, are constricted and the pipe ends 10 are clamped upon these constricted portions by means of a pair of retaining strips 19 which are tightened together by screws 20.

A very simple and advantageous connection of the pipe ends 10 of the heat-exchanger element 8 which project through the bores 12 in the wall 11 to the inside of the header 7 is illustrated in FIGS. 10 and 11. A tight connection of the pipe ends 10 is in this case attained by coiled compression springs 21 which are inserted into the header 7 and engage with their upper ends in blind bores 22 diametrically opposite to the bores 12 in the wall of the header 7, their lower ends carrying conical bushings 23 which, when the springs 21 are only partly compressed as shown in FIG. 10, project into the associated bores 12. If the heat-exchanger element is then moved toward the header 7 in the direction of the arrow 24, as shown in FIG. 11, and the pipe ends 10 are inserted into the bores 12 of the header, these pipe ends will also slide over the conical bushings 23 and the latter will then compress the springs 21. When the pipe ends 10 are inserted so far into the bores 12 as to project through the wall of header 7 to the inside thereof, the force of springs 21 will press the conical bushings 23 into the pipe ends so that the bushings will then exert a radially outward pressure upon the pipe ends 7 and press these ends tightly against the walls of the bores 12. The end portions of pipes 2 which project into the header 11 will then also be expanded in the same manner as previously described with reference to FIG. 7.

FIGS. 12 to 14 illustrate three coil springs 25 to 27 which are provided at one end with windings 28 of a conical shape which serve the same purpose as the conical bushings 23 according to FIGS. 10 and 11 so that these bushings may be omitted. Spring 26 according to FIG. 13 is extended beyond the conical winding 28 by a few cylindrical turns 29.

FIG. 15 illustrates a manner in which several identical heat-exchanger elements similar to those shown in FIGS. 1 to 4 may be combined so as to form a heat-exchanger block 31 by means of generally rectangular spacing bars 30 whose major sides are shaped to conform to the contours of the outer sides of two adjacent heat-exchanger elements, i.e., are indented to receive the adjoining halves of the pipes 2 of the pair of units in positive contact therewith. In this particular example, the spacing bars 30 are designed to interconnect a plurality of heat-exchanger elements 1 according to FIG. 1 and may be glued or welded to the adjacent elements 1. The spacing bars 30 may, however, also be connected to the heat-exchanger elements and to one another by means of rivets, screws, or the like or by means of tie rods. In the latter case, the pipes 2 of the adjacent heat-exchanger elements 1 should be located in

corresponding positions and the tie rods may be passed through bores 32 in corresponding connecting webs 3 of the heat-exchanger elements as shown in FIG. 16.

FIG. 17 illustrates a heat-exchanger block 33 in which the units 34 to 37 are located within a common plane and connected in series with one another by means of headers 38 to 42 so that the heating medium flows through the different heat-exchanger elements 34 to 37 and the headers 38 to 42 in the directions indicated by the arrows 43. In order to permit the headers 38 to 42 to expand in their longitudinal directions upon an increase in temperature, their closed ends of coaxial headers 38, 40, and 39, 41 are slidably interconnected by coupling sleeves 44 to 46 which permit each individual header 38 to 42 to shift longitudinally in the direction of the arrows 47 so that no thermal stresses will occur within this entire heat-exchanger block 33.

FIG. 18 illustrates another heat-exchanger block 48 with a different arrangement of its elements. In this case, the coplanar heat-exchanger elements 49 and 50 and the elements 51 and 52 form two pairs, with the elements of each pair connected in series and each pair connected at one end by a header 53 or 54 to a supply duct or pipe 55 for the heating medium and at the other end by a header 56 or 57 to a discharge duct or pipe 58 therefor. The outer ends of the two heat-exchanger elements 49, 50 and 51, 52 of each pair are, however, connected to each other by common headers 59 and 60, respectively. The direction of flow of the heating medium passing through this heat-exchanger block 48 is again indicated by the arrows 43.

In both heat-exchanger blocks 33 and 48 according to FIGS. 17 and 18 the fact must be considered that the coefficient of thermal expansion of plastic is approximately six times as high as that of metal. Therefore, if the headers 38 to 42 of the heat-exchanger block according to FIG. 17 and the headers 53 to 60 of the heat exchanger block according to FIG. 18 consist of metal, the outer headers 39 and 41 or 59 and 60 of the two blocks must be slidably mounted. In the heat-exchanger block 48 according to FIG. 18, this may be attained, for example, by mounting the lower ends of the two headers 59 and 60 on rollers 61 which are capable of moving along a supporting surface such as, for example, the floor of the room in which this heat-exchanger block is installed.

The two heat-exchanger blocks 33 and 48 according to FIGS. 17 and 18 may be employed for producing a larger heat output especially since they may be enlarged without difficulty in a direction vertical to the plane of these Figures. The different sets of heat-exchanger elements 34 to 37 or 49 to 52, respectively, are then to be combined into larger units, regardless of whether they are to be connected in series or in parallel with one another.

Although my invention has been illustrated and described with reference to preferred embodiments thereof, I wish to have it understood that it is in no way limited to the details of such embodiments but is capable of numerous modifications within the scope of the appended claims.

Having thus fully disclosed my invention, I claim:

1. A heat exchanger comprising at least one unitary element of plastic material consisting of a multiplicity of thin-walled parallel pipes molded integrally with one another and with connecting webs maintaining said pipes transversely spaced.
2. A heat exchanger as defined in claim 1 wherein said pipes are divided into several sets of at least two adjacent pipes each, the axes and connecting webs of successive sets lying alternately in two parallel planes.
3. A heat exchanger as defined in claim 1 wherein said pipes have ends projecting beyond said webs, further comprising a header interconnecting said pipes, said header being anchored to said projecting ends.
4. A heat exchanger as defined in claim 3 wherein said header has a set of bores respectively traversed by said projecting ends.
5. A heat exchanger as defined in claim 4 wherein said projecting ends have extremities extending past said bores,

further comprising wedge means in said header engaging in said extremities for dilating same.

6. A heat exchanger as defined in claim 5 wherein said wedge means comprises a set of tubular screws with conical heads of a diameter exceeding the inner pipe diameter.

7. A heat exchanger as defined in claim 5 wherein said wedge means comprises a set of compression springs aligned with said pipes and terminating in conical spreaders for said extremities, said springs bearing upon an inner wall surface of said header remote from said bores.

8. A heat exchanger as defined in claim 7 wherein said springs are coiled, said spreaders consisting of tapering turns of the coils.

9. A heat exchanger as defined in claim 7 wherein said spreaders are tubular inserts carried by said springs.

10. A heat exchanger as defined in claim 3 wherein said header has a set of bores confronting said projecting ends, further comprising nipples seated in said bores and connected with said projecting ends outside the header.

11. A heat exchanger as defined in claim 10 wherein said nipples have bulb-shaped outer ends received in said projecting ends, the latter being shrunk onto said nipple.

12. A heat exchanger as defined in claim 10 wherein said nipples have constricted outer ends received in said projecting ends, further comprising external clamping means holding said projecting ends onto said constricted ends.

13. A heat exchanger comprising a plurality of unitary elements as defined in claim 1 transversely spaced from one another and a generally rectangular spacer inserted between a pair of said elements in positive engagement therewith, said spacer having major sides indented to receive the adjoining halves of the pipes of said pair of elements.

14. A heat exchanger as defined in claim 13 wherein said spacer is bonded to said pair of elements.

15. A heat exchanger as defined in claim 13 wherein said connecting webs of said pair of elements are provided with apertures accommodating fastening means for holding said spacer in position therebetween.

16. A heat exchanger as defined in claim 13 wherein at least two of said elements are juxtaposed with their pipes coplanar, further comprising individual headers for said elements respectively connected with the pipes thereof at one end of each element and a common header connected with the pipes of all said elements at the opposite end.

17. A heat exchanger as defined in claim 16 in which said headers are movable independently of one another in their longitudinal directions.

18. A heat exchanger as defined in claim 16 wherein said individual headers are coaxially disposed and provided with coupling sleeves establishing a fluid path therebetween.

19. A heat exchanger as defined in claim 16 wherein said elements are divided into two groups of at least two elements each, the elements of each group being provided with a common header at said opposite end, further comprising a supply duct communicating with an individual header of each group and a discharge group communicating with another individual header of each group with establishment of a fluid path from said supply duct to said discharge duct by way of said individual and common headers.

20. A heat exchanger as defined in claim 19 wherein said groups are provided with mounting means enabling relative movement thereof in response to thermal expansion and contraction.

HEAT-EXCHANGER COMPONENTS

**THE PATENT IS HEREBY AMENDED AS
INDICATED BELOW.**

Matter enclosed in heavy brackets **[ ]** appeared in the patent, but has been deleted and is no longer a part of the patent; matter printed in italics indicates additions made to the patent.

AS A RESULT OF REEXAMINATION, IT HAS
BEEN DETERMINED THAT:

Claims 1-20 having been finally determined to be 20 unpatentable, are cancelled.

New claims 21-38 are added and determined to be patentable.

21. *For use in a heat exchanger wherein a medium flows through heat exchanger means comprising*

- (a) a plurality of generally flat integrally extruded plastic unitary elements arranged in a common plane and each comprising*
  - i. a plurality of thin walled parallel pipes of circular cross section, and*
  - ii. interconnecting webs between adjacent pipes;*
- (b) the webs at each end of each element being cut away from projecting pipe ends; and*
- (c) a pair of headers each having a series of parallel spaced bores with which the projecting pipes at opposite ends of each element communicate.*

22. *Heat exchanger means as defined in claim 21 wherein said pipes are divided into several sets of at least two adjacent pipes each, the axes and connecting webs of successive sets lying alternately in two parallel planes.*

23. *Heat exchanger means as defined in claim 21 wherein said projecting ends have extremities extending past said bores, further comprising wedge means in said header engaging in said extremities for dilating same.*

24. *Heat exchanger means as defined in claim 23 wherein said wedge means comprises a set of tubular screws with conical heads of a diameter exceeding the inner pipe diameter.*

25. *Heat exchanger means as defined in claim 23 wherein said wedge means comprises a set of compression springs aligned with said pipes and terminating in conical spreaders for said extremities, said springs bearing upon an inner wall surface of said header remote from said bores.*

26. *Heat exchanger means as defined in claim 25 wherein said springs are coiled, said spreaders consisting of tapering turns of the coils.*

27. *Heat exchanger means as defined in claim 25 wherein said spreaders are tubular inserts carried by said springs.*

28. *Heat exchanger means as defined in claim 21 wherein said header has a set of bores confronting said projecting ends, further comprising nipples seated in said bores and connected with said projecting ends outside the header.*

29. *Heat exchanger means as defined in claim 28 wherein said nipples have bulb-shaped outer ends received in said projecting ends, the latter being shrunk onto said nipple.*

30. *Heat exchanger means as defined in claim 28 wherein said nipples have constricted outer ends received in said projecting ends, further comprising external clamping means holding said projecting ends onto said constricted ends.*

31. *Heat exchanger means comprising a plurality of unitary elements as defined in claim 21 transversely spaced from one another and a generally rectangular spacer inserted between a pair of said elements in positive engagement therewith, said spacer having major sides indented to receive the adjoining halves of the pipes of said pair of elements.*

32. *Heat exchanger means as defined in claim 31 wherein said spacer is bonded to said pair of elements.*

33. *Heat exchanger means as defined in claim 31 wherein said connecting webs of said pair of elements are provided with apertures accommodating fastening means for holding said spacer in position therebetween.*

34. *Heat exchanger means as defined in claim 31 wherein at least two of said elements are juxtaposed with their pipes co-planar, further comprising individual headers for said elements respectively connected with the pipes thereof at one end of each element and a common header connected with the pipes of all said elements at the opposite end.*

35. *Heat exchanger means as defined in claim 34 in which said headers are movable independently of one another in their longitudinal directions.*

36. *Heat exchanger means as defined in claim 34 wherein said individual headers are coaxially disposed and provided with coupling sleeves establishing a fluid path therebetween.*

37. *Heat exchanger means as defined in claim 34 wherein said elements are divided into two groups of at least two elements each, the elements of each group being provided with a common header at said opposite end, further comprising a supply duct communicating with an individual header of each group and a discharge group communicating with another individual header of each group with establishment of a fluid path from said supply duct to said discharge duct by way of said individual and common headers.*

38. *Heat exchanger means as defined in claim 37 wherein said groups are provided with mounting means enabling relative movement thereof in response to thermal expansion and contraction.*

* * * * *
